FLOOR CLEANING MACHINE

Jack L. Burgoon, Toledo, Ohio, assignor to The Scott & Fetzer Company, Lakewood, Ohio

Filed June 25, 1970, Ser. No. 23,670

Term of patent 14 years

Int. Cl. D15—05

U.S. Cl. D37—3

FIG. 3 -

FIG. 4 -

FIG. 5 -

FIG. 1 is a front view in perspective of a floor cleaning machine showing my new design;

FIG. 2 is a left side view in elevation of the machine;

FIG. 3 is a top view of the machine;

FIG. 4 is a back view in elevation of the machine; and

FIG. 5 is a front view in elevation of the machine.

What I claim is:

The ornamental design for a floor cleaning machine, substantially as shown.
